UNITED STATES PATENT OFFICE.

JOHN HENRY DEWHURST, OF SHEFFIELD, ENGLAND.

LADLE FOR CARRYING AND TIPPING BLAST-FURNACE SLAG.

No. 906,117.

Specification of Letters Patent.

Patented Dec. 8, 1908.

Application filed February 19, 1908. Serial No. 416,700.

To all whom it may concern:

Be it known that I, JOHN HENRY DEWHURST, subject of England, residing at 68 Attercliffe road, in the city of Sheffield, in the county of York, England, have invented new and useful Improvements in Ladles for Carrying and Tipping Blast-Furnace Slag, of which the following is a specification.

My present invention is for improvements and modifications in ladles such as form the subject matter of my U. S. A. Patents Nos. 740,404 and 740,405, both dated 6th October 1903.

It has been found in practice that the ladles which formed the subject matter of the patents herein referred to, notwithstanding the methods which have been employed for strengthening them, have been liable to crack through the continual expansion and contraction which is produced through the fluctuations in temperature to which they are subjected when in use, and it has also been found that the trunnions, more particularly the twin or double trunnions, are liable to rapid wear, and the object of my present invention is to obviate these defects.

The nature of my invention will be better understood on reference to the accompanying sheet of drawings in which,

Figure 1, is a side elevation of one of my improved slag ladles. Fig. 2, is an end elevation and Fig. 3, a plan of the same. Fig. 4, is an end elevation of the protective shield for the trunnions, and Fig. 5, is a side elevation of the same.

The same letters refer to similar parts throughout the several views.

In order to prevent the ladles from crack-

ing, I cast them in halves longitudinally, *i. e.*, in a line, A. B. transverse to the centers of the trunnions, *a*, *b*, and join them together with pins and cotters, dowels or bolts, *c*. The advantage of making the joint longitudinally is, that it does not interfere with the scour of the metal when the ladle is tipped, as has been found to be the case when the joints have been made transversely or parallel with the centers of the trunnions. I also obviate the tendency of the wear of the trunnions, *a*, *b*, by covering their wearing surfaces with protective shields, *d*, of hard steel or other equivalent metal and I form them of such a shape that they can be shrunk on when hot and retain a firm grip in the required position.

Protective shields as herein described are applicable for repairing or renewing the surfaces of the trunnions of ladles which have not been protected in the first instance and which have become worn by use.

What I do claim and desire to secure by Letters Patent is:

A slag ladle consisting of two parts divided from each other vertically, means for holding the two parts together and trunnions, the joint between the two parts extending longitudinally of the ladle and in a plane at right angles to the vertical plane in which the trunnions lie, substantially as described.

In testimony whereof I have signed my name to this specification in the presence of two subscribing witnesses.

JOHN HENRY DEWHURST.
